UNITED STATES PATENT OFFICE.

GEORGE ADOLPH JOHNSON, OF MUSKEGON, MICHIGAN.

WINDER-SHAFT COLLAR.

1,183,204.

Specification of Letters Patent.

Patented May 16, 1916.

Application filed August 5, 1915. Serial No. 43,726.

To all whom it may concern:

Be it known that I, GEORGE A. JOHNSON, a citizen of the United States, residing at Muskegon, county of Muskegon, and State 5 of Michigan, have invented certain new and useful Improvements in Winder-Shaft Collars, of which the following is a specification.

This invention relates to winder shaft col- 10 lars.

The present invention relates to those de- 15 vices which are used on the winder or expansion shaft of paper slitting and winding machines for the purpose of blocking or holding the ends of the paper roll being wound and slit.

In winding a wide sheet of paper, being 20 cut into several rolls on the winder or expansion shaft, if there is any end slip of the paper, the several cuts will interlock so that when the winder or expansion shaft is removed for the purpose of breaking the rolls apart, there will be imperfect ends on the rolls. A common practice is to catch a small 25 rope or binder twine several feet long around the winder shaft while it is in motion. This is a dangerous operation and causes many accidents.

My object is to provide an improved safety 30 collar two of which can be initially placed on the end portions of the winder or expansion shaft and, after the roll has assumed sufficient diameter to permit the improved safety collars to be slid inwardly 35 against the ends of the paper roll, such action may be had with a result that the collars will automatically grip the winder or expansion shaft and resist lateral spread or displacement of the paper roll being wound 40 and cut into a plurality of rolls.

With my invention, the pressure of the paper roll being wound, when it tends to work outwardly, longitudinally of the winder shaft, results in a pressure on the 45 collars which, by reason of the construction provided, causes the collars to tighten their grip on the winder roll.

My invention embraces certain improved 50 features and novel combinations of parts, one embodiment of which I have set forth fully hereinafter and shown in the accompanying drawings, but I wish it understood that this is by way of illustration of the invention and not in restriction of the scope 55 thereof, as changes may be resorted to without affecting the principle of the invention.

In the accompanying drawings: Figure 1 is a front view, of somewhat diagrammatic character, showing a pair of the safety collars in use; Fig. 2, an end diagrammatic view of the rolls and drums of a paper winding and slitting machine showing the arrangement when the paper web is first started on the winder or expansion roll; Fig. 3, a longitudinal detail section through the collar; Fig. 4, a cross section on line 4—4, Fig. 3; and Fig. 5, a detail perspective of one of the gripping dogs.

Referring first to Fig. 2, the driving drums are shown at 1 and the binder roll 2; the winder or expansion roll is shown at 3. At the time the paper web 4 is started to wind on the roll 3, the drums and rolls are in the position shown in Fig. 2. At the beginning of the winding operation, the relatively small diameter of the shaft or roll 3 prevents the placing of my improved safety collars in the proper position to prevent lateral spreading of the paper, but these safety collars, shown, generally, at 5, Fig. 1, may 80 be first placed on the winder roll 3 in the position shown in dotted lines, Fig. 1, and when the web 4 has been wound around the roll 3 until the diameter of the wound roll is slightly greater than that of the safety collar 85 5, a stick may be employed to push the safety collars up against the ends of the wound and slit paper roll 6, as shown in Fig. 1. On further winding and slitting, the safety collars automatically lock and retain themselves in 90 the position shown and the lateral pressure exerted by the wound roll 6 only tends to cause the safety collars to grip the winder roll 3 more tightly. The safety collars, therefore, prevent lateral spreading of the roll 6, 95 and consequently, the slitting is perfect and there is no interlocking of the several cuts 7 which define the plurality of independent rolls 8 wound on the roll 3. The ends of the respective rolls 8 are, therefore, relatively 100 smooth and perfect.

Having described the manner of use and operation, reference is to be had to Figs. 3, 4, 5, for a disclosure of the construction of the safety collars 5. As the collars 5 are duplicates, a description of one will suffice. The outer shell 9 is cylindrical on its exterior and provided at its inner end with an inwardly projecting flange 10 which is of a size adapted to accommodate the winder or expansion roll 3 and also serves as a face to bear against the ends of the paper roll 6 and,

further, to prevent disconnection of the inner locking mechanism contained within the shell 9. The shell 9 is of two different diameters, as shown at 11 and 12, the part 11 being nearest the flange 10 and the part 12 leading in from the outer end of the shell 9. The parts 11 and 12 are connected by a sloping or tapered annular portion 13 which serves as a cam to cause the gripping dogs to operate. Contained within the shell 9 is a cage or bushing 14 which has an annular flange 15 adapted to coöperate with the ring 16 secured to shell 9 to prevent the bushing from coming out of the shell 9, but the relationship of the parts is such that the cage or sleeve 14 may have a movement of limited extent lengthwise within the shell 9. At its inner end the bushing or sleeve 14 has secured thereto by screws 17, a ring 18. Extending longitudinally of, and through the walls of the bushing 14 are slots 19 in which play the gripping dogs 20 which are pivoted at their inner ends so that they can expand and contract radially of the bushing, by screws 21 which are loosely set in holes 22 in the ring 18. The free ends of the dogs overlap the bushing and are pressed outwardly by suitable springs 23. The outer faces of the dogs comprise a part 24 substantially flush with the exterior of the bushing or sleeve 14, a part 25 adapted to bear against the surface 12 and an inclined or cam part 26 which may be made to engage the inclined annular surface 13 when the bushing 14 is pushed inwardly in relation to the shell 9. When the bushing is slightly projected, the cam surfaces 26 and 13 are free of each other and the springs then expand the dogs so that they do not grip the winder shaft 3, but when the bushing is pushed into the shell 9, the cam surfaces come together and the inner gripping faces of the dogs then bear against the winder shaft 3. This is the action which occurs when the safety collars are pushed inwardly from the dotted line to the full line position of Fig. 1. A similar effect is obtained by the lateral pres-

sure exerted by the outermost paper rolls 8 as they press against the shell 9 and hence 50 the dogs are made to even more tightly grip the winder shaft 3, due to such pressure.

I preferably provide on the inner faces of the dogs rubber or friction facings or pads 27 which may usually be sufficient to 55 hold the collar, but in addition thereto, there are provided teeth, projections or corrugations 28 so that if the gripping pads 27 fail to hold the collar, through wear or too great pressure, the teeth will bite into 60 the shaft or roll 3 and hold the collar.

Having thus described my invention, what I claim as new and desire to secure by Letters Patent, is:—

1. A collar for winder rolls comprising 65 an outer shell, an inner bushing, said shell and bushing being relatively, freely slidable and locking dogs or grippers adapted to be set or released by relative sliding movement of said shell and bushing. 70

2. A collar for winder rolls comprising an outer shell and an inner bushing adapted for relative free, sliding movement, and locking dogs carried by the bushing adapted to coöperate with the shell to be set when 75 the shell moves in a given direction and for release when said shell moves in an opposite direction.

3. A collar for winder rolls comprising an outer shell and an inner bushing adapt- 80 ed for relative free, sliding movement, locking dogs carried by the bushing, a cam surface being provided on the shell adapted to actuate said dogs.

4. A collar for winder rolls comprising an 85 outer shell and an inner bushing adapted for relative free, sliding movement, locking dogs hinged or pivoted to the bushing and provided with cam faces, and spring means for actuating said dogs, a cam mem- 90 ber being provided on the shell adapted to coöperate with the dogs.

In testimony whereof, I hereunto affix my signature.

GEORGE ADOLPH JOHNSON.
